UNITED STATES PATENT OFFICE.

JOSEPH CELENKO, OF BEDFORD, OHIO.

RUBBER HEEL.

Application filed February 7, 1928. Serial No. 252,513.

The present invention relates to rubber heels and has for its prime object to provide a shoe in combination with a rubber heel and means for detachably mounting the rubber heel on the heel of the shoe, so that the detaching and renewing of the rubber heel may be accomplished by an unskilled person in a short amount of time, with convenience and ease.

10 A still further very important object of the invention resides in the provision of the arrangement of tacks or nails in the application of the heel layers to the sole of the shoe so as to provide a strengthened and 15 reinforced portion for each of the screw elements used for detachably connecting the rubber heels to the heel portion of the shoe.

20 A still further very important object of the invention resides in the provision of a shoe of this nature which is simple in its construction, inexpensive to manufacture, strong and durable, thoroughly efficient and reliable in its use and otherwise well adapted for the purpose for which it is designed.

With the above and numerous other objects in view as will appear as the description proceeds, the invention resides in certain novel features of construction, and in the 30 combination and arrangement of parts as will be hereinafter more fully described and claimed.

In the drawing,

35 Figure 1 is a fragmentary bottom plan view of a shoe showing the leather heel portion thereof.

Figure 2 is a similar view showing the rubber heel applied thereto.

40 Figure 3 is a vertical section through the heel portion of the shoe and the rubber heel.

Figure 4 is a bottom plan view of another embodiment of the rubber heel.

Figure 5 is a similar view showing still another embodiment thereof.

45 Referring to the drawings in detail, it will be seen that the numeral 5 denotes the sole of the shoe and the numeral 6 denotes the leather heel portion thereof. This leather heel portion thereof is tacked to the 50 heel portion of the sole 5 by means of a plurality of groups of tacks or nails 7, arranged in groups of four with a slight space there-

between for the reception of screws 8 so as to strengthen the leather heel 6 at these portions so as to prevent the screws from being 55 easily pulled out.

The numeral 9 denotes a rubber heel having apertured plates 10, embedded therein and said heel is provided with countersunk openings when registering with the apertures of the plate 10. The heel 9 is placed on the heel 6 and the screws 8 are inserted through the openings 11 in the apertures of the plates 10 and then embedded in the heel 6 between the nails or tacks 7 arranged in 65 the groups of four as explained. If desired, the heel 9 may be made in sections, such as is illustrated in Figures 4 and 5, at 9' and 9^a respectively. These sections are formed in accordance with the tendency of the person who wears the heel. Some people wear the heels at their rear ends and other people wear their heels on the sides. Obviously, when the heel is sectional as shown in Figures 4 and 5, only the worn section has to 70 be renewed.

75 It will be seen from this invention that any unskilled person may easily detach the heel 9 or portions of the heels 9' and 9^a and replace the same, thus eliminating the necessity of 80 going to the shoemaker and wasting considerable time besides being subjected to additional expense.

It is thought that the construction, utility and advantages of this invention will now be 85 quite apparent to those experienced in this art without a more detailed description thereof. The present embodiment of the invention has been disclosed in detail merely by way of example, since in actual practice it 90 attains the features of advantage enumerated as desirable in the statement of the invention and the above description.

95 It will be apparent that changes in the details of construction and in the combination and arrangement of parts may be resorted to, without departing from the spirit or scope of the appended claims, or sacrificing any of its advantages.

Having thus described my invention, what 100 I claim as new is:

1. In combination with a shoe provided with a leather heel, of a plurality of nails distributed in groups for holding the heel to the

shoe, the nails in each group being relatively very closely grouped, a rubber heel having a plurality of apertures, screws extending through the apertures and embedded in the 5 first mentioned heels between the nails of the groups.

2. In combination with a shoe provided with a leather heel, of a plurality of nails distributed in groups for holding the heel to the 10 shoe, the nails in each group being relatively

very closely grouped, a rubber heel having a plurality of apertures, screws extending through the apertures and embedded in the first mentioned heel between the nails of the groups, and plates embedded in the rubber heel and apertured with their apertures in registry with the openings in the rubber heel. 15

In testimony whereof I affix my signature.

JOSEPH CELENKO.
